UNITED STATES PATENT OFFICE.

HANS FLEISSNER, OF PRIBRAM, AUSTRIA-HUNGARY.

FIRE-DAMP DETECTOR.

1,202,697.

Specification of Letters Patent.

Patented Oct. 24, 1916.

Application filed November 26, 1915. Serial No. 63,657.

To all whom it may concern:

Be it known that I, HANS FLEISSNER, a subject of the Emperor of Austria-Hungary, and residing at Pribram, Austria-Hungary, have invented new and useful Improvements in Fire-Damp Detectors, of which the following is a specification.

My invention relates to the detection of fire-damp, its object being to provide an apparatus which is able to indicate the presence of fire-damp.

My novel fire-damp detector is based on the phenomenon of the singing flame.

If a flame is placed into a certain position within a hollow body open at two ends and adapted for the production of sound through oscillation of the air within the said body, a sound will be produced which ceases on the flame being moved into another position. If the distance between the first flame position in which the sound producing body sounded, and the second position in which the sound production ceased is not too great the sounding will again set in when the air within the hollow body is intermixed with explosive gases; thus the sounding of the hollow body indicates the presence of explosive gases in the air. My novel fire-damp detector is based on this principle, and may be so constructed that the same can be used as a miner's lamp. The flame in my detector is adapted to be moved within the second chamber, and the apparatus can thereby be adjusted to detect even small proportions of mine-gas.

In the accompanying drawing I have illustrated a preferred embodiment of my invention, in elevation, and partly in section.

Referring to the drawing, *a* is the container for the fuel and *b* the burner. The burner *b* is provided with a toothed rack *b'* which is engaged by a pinion *c* by means of which the burner can be raised or lowered. The burner *b* is incased in a glass tube *d* which terminates at its lower end slightly above the upper face of the container *a* and is fixedly mounted in a downward projecting extension *f* of a hollow globe or ball *e*. At its head the hollow globe *e* carries the chimney *g*. The tube *d* is incased in a larger glass tube *h* of the type usually employed in miners' lamps. A mantle *i* of wire-work extends from the upper end of the tube *h* to the globe *e* and allows air to pass to the burner *b*. To further safe-guard against

fire-damp explosion, the chimney *g* is inclosed in a wire-work casing *k*. The parts are supported in a frame *l* in a manner well known for instance, with miners' lamps, a hook *m* being provided by means of which the lamp can be conveniently carried about.

My novel fire-damp detector is used as follows: The position of the burner is adjusted so that the flame produces a sound, whereupon the burner is moved until the sound ceases. If now explosive gases enter the interior of the hollow body surrounding the flame, the sounding will start anew. To detect very small proportions of mine-gas the flame may be adjusted to sound weakly in pure air. When explosive gases mix with the air within the lamp, the sounding becomes stronger and a change occurs in the tone-color of the sound.

The hollow globe *e* is especially suited for the purpose of my fire-damp detector. However the hollow body, to answer certain requirements, may be given a form that is essentially different from the form shown in the drawing. For the effective operation of the lamp a sufficient draft is a requisite; the dimensions of the hollow body as well as the dimensions of the inlet and outlet openings will have to be chosen accordingly.

To produce a flame, any suitable liquid gaseous or solid fuel may be employed.

It is obvious that various modifications may be made as regards the form and disposition of the parts of my fire-damp detector, without thereby involving any departure from the spirit and scope of my invention.

What I claim as my invention and desire to secure by Letters Patent of the United States, is:

1. A fire-damp detector, comprising in combination, a fuel container, a burner, a hollow globe, a chimney on said globe, and an extension on said hollow globe, said extension being disposed so as to inclose said burner, whereby the flame of said burner is adapted to produce a sound within said extension.

2. A fire-damp detector, comprising in combination, a fuel container, a burner in connection with said container, a tubular structure surrounding said burner and extending above said burner, an enlarged portion in said tubular structure, an air admitting space at the lower end of said tubular structure, and means for longitudinally ad-

justing the position of said burner within said tubular structure, whereby the flame of said burner may be moved into a sounding position and out of a sounding position.

- 5 3. A fire-damp detector, comprising in combination, a fuel container, a burner connected with said container, means for varying the position of said burner relatively to said container, a tube surrounding said 10 burner and extending above said burner, an enlarged portion in said tube and intermediate its ends, an air admitting space at the lower end of said tube, and means for rendering the detector safe against explosion.
- 15 4. A fire-damp detector miner's lamp comprising a burner, a resonant tube surrounding said burner and adapted to emit sound induced by the flame of the burner, means for adjusting one of said elements with relation to the other to vary or silence the 20 sound of the flame, an outer tube surrounding and spaced from said resonant tube, a globe surmounting said resonant tube, and a wire gauze mantel between said outer tube 25 and globe, said parts being operative to pro-

duce or increase a singing sound whenever a fire-damp gas is admitted to the lamp.

5. A fire-damp detector miner's lamp comprising a burner, a resonant tube surrounding said burner and adapted to emit sound induced by the flame of the burner, means for adjusting one of said elements with relation to the other to vary or silence the sound of the flame, an outer tube surrounding and spaced from said resonant tube, a 30 globe surmounting said resonant tube, a wire gauze mantle between said outer tube and globe, a chimney extending upward from the top of said globe, and a wire gauze casing surrounding said chimney, said parts being operative to produce or increase a singing sound whenever a fire-damp gas is admitted to the lamp. 35

In testimony whereof I have hereunto affixed my signature.

DR. HANS FLEISSNER.
